DESIGN FOR A PICTURE MAT

Harvey A. Prew, Providence, R. I.

Application February 15, 1934, Serial No. 50,738

Term of patent 7 years

To all whom it may concern:

Be it known that I, HARVEY A. PREW, a citizen of the United States of America, residing in Providence, county of Providence, State of Rhode Island, have invented a new, original, and ornamental Design for a Picture Mat, of which the following is a specification, reference being had to the accompanying drawing forming a part thereof.

Fig. 1 is a front perspective view of a picture mat, showing my new design; Fig. 2 is a rear perspective view; and Fig. 3 is a section on line 3—3 of Fig. 1, of the same.

I claim:

The ornamental design for a picture mat, substantially as shown.

HARVEY A. PREW.
